UNITED STATES PATENT OFFICE

2,044,510

SETTING JEWELS

Alfred F. Reilly, North Attleboro, Mass., assignor
to Evans Case Company, North Attleboro,
Mass., a corporation of Massachusetts

Application March 24, 1936, Serial No. 70,686

5 Claims. (Cl. 63—26)

The present invention relates to setting stones, jewels and the like and is particularly directed to those cut with upwardly and inwardly inclined side or end walls or both. A type of such stone is referred to as cabochon and the stone may be of any suitable or desirable size and general shape. The invention is illustrated and described with reference to relatively long, narrow stones or jewels, but it may also be adapted to jewels of other forms.

In general the invention consists of a setting having some walls which are pre-formed to substantially correspond to the walls of the jewel or stone they are to receive. When the stone is placed within these walls it may be clasped and held therein, and the ends of the walls of the setting, at least at their upper edges extend beyond the stone or jewel and may be bent inwardly to enclose, clasp and hold permanently in position the stone or jewel.

Such a jewel setting may be adapted for use in any particular arrangement or connection, such as rings, pins, pendants, or other jewelry. The setting is also adapted to ornamenting the surfaces or ends of boxes and receptacles of various sorts and for illustrative purposes such an adaptation is illustrated and described herein.

In the accompanying drawing which shows forms the invention may take Figure 1 is a plan view of a setting showing a cabochon stone partially in place. Fig. 2 is a plan view of a setting showing a cabochon stone in final position. Fig. 3 is a plan view showing a cabochon stone in the setting in its finished or completed form. Fig. 4 is a longitudinal vertical section on the line 4—4 of Fig. 3. Fig. 5 is a transverse vertical section of a stone in its mounting placed on the end of a receptacle or case, a fragment of which is illustrated. Fig. 6 is a fragmentary perspective view of one end of a stone in the completed mounting such as illustrated in Fig. 3. Fig. 7 is a transverse vertical section similar to Fig. 5 showing another form of mounting associated with or forming the end of a receptacle or case, a fragment of which is illustrated.

A cabochon stone 10 is illustrated as having upwardly and inwardly inclined side walls 11 and it may also have upwardly and inwardly inclined end walls 12. A sheet of metal is bent to form a base 13 with upwardly and inwardly inclined side walls 14 formed to substantially correspond in shape with the lower outline of the side walls 11 of the stone 10. The elongated stone 10 may thus be slid longitudinally between the side walls 14 as illustrated in Fig. 1. The stone 10 may be moved

inwardly until it reaches its final position indicated in Fig. 2. In this position the end of the stone 10 will be stopped, engaged and held by the inwardly turned upper corners 15 of the side walls 14. The corners 15 may be turned in to the appropriate extent before the stone 10 is placed in the mounting as indicated in Fig. 1, or they may be turned in to the extent allowed by the stone after it has reached its final position indicated in Fig. 2. It will be noted in Fig. 2 that the corners 10 at the other ends of the walls 14 are not turned in, thus allowing insertion of the stone 10. After the stone 10 has reached its final position as indicated in Fig. 2 the upper corners 16 of the walls 14 at the ends opposite the corners 15 may be turned in 15 to engage and hold the stone 10 as indicated in Fig. 3. In the finished condition as indicated in Fig. 3 it will be observed that the stone is tightly grasped by its base and held securely in position in the setting. The side walls 14 are shown extending through the entire length of the stone 10, and grasping it on both sides, holding it down against the base 13, as shown, but this is not essential since the side walls may be made in several separated portions and need not extend 25 throughout the entire length of the stone. The grip of the walls 14 on the stone holds it from leaving its seat and it may be held from longitudinal movement by contact of the corners 15 and 16 with its ends 12 whether or not the ends of the 30 stone are inwardly inclined. As shown the in-turned corners 15 and 16 grasp snugly the inclined walls 12 of the stone 10 and tend to hold it not merely against lateral or longitudinal displacement but also against any movement away 35 from the base 13.

The entire setting either before or after having the stone placed therein may be attached to any suitable device such as chain, pin, surface or the like. It is shown attached to an end or side 40 17 of a casing or receptacle diagrammatically illustrated in Fig. 5. The base 13 may be attached to the member 17 by any suitable means such as riveting, soldering, brazing, or welding, and preferably it will be attached before receiving the 45 stone 10 so as to avoid injury to the stone.

In Fig. 7 is illustrated an optional form of setting in which the side walls 14 of the setting are connected by a base member which has short turned-in portions 18 at each side against which the stone 10 rests and beyond which the base member is turned away from the stone 10 to form members 19 between which is a transverse base member 20 which is separated somewhat from the stone 10. The stone is held between the walls 55

14 and the portions 18. Either or both the base members 18 and 19 are adapted to be engaged by or attached to the walls 21 of a receptacle diagrammatically illustrated in Fig. 7 in such a way 5 that the base member 20 may itself form one wall of the receptacle. The base members 18 and 19 may be attached to the receptacle walls 21 by riveting, soldering, brazing, welding or in any other suitable way, either before or after the stone 10 is put in place. Preferably the base member 10 will be attached to the receptacle and become a part thereof prior to insertion of the stone 10 so as to avoid unnecessary handling and possible marring of the stone 10. The base may be thus 15 permanently attached to the walls 21 or one of more of the walls 21 may perform the function of a cover to the receptacle, and instead of being permanently attached to the members 18 and 19 may merely find a seat against them when closed.

20 The particular form and constructions herein illustrated and described are not essential to the invention which may find other embodiments.

I claim as my invention:

1. A setting for a jewel having upwardly inwardly inclined sides and ends, comprising side walls formed to engage and substantially fit the sides of the jewel and having ends adapted to be turned in to engage the ends of the jewel.

2. A setting for a jewel having upwardly inwardly inclined sides and ends, comprising side walls formed to engage and substantially fit the sides of the jewel, and each side wall having one end turned in to engage one end of the jewel, and each side wall having the other end adapted to be turned in to engage the other end of the jewel. 5

3. A setting for a jewel having upwardly inwardly inclined sides and ends, comprising side walls formed to engage and substantially fit the 10 sides of the jewel and having ends adapted to be turned in to engage the ends of the jewel, and a base member joining the side walls having an inset portion so as to form an end to a receptacle and a seat for attachment of the sides of the re- 15 ceptacle.

4. A setting for a jewel having upwardly inwardly inclined sides, comprising side walls formed to engage and substantially fit the sides of the jewel and having ends adapted to be turned in 20 to engage the ends of the jewel.

5. A setting for a jewel having upwardly inwardly inclined sides, comprising side walls formed to engage and substantially fit the sides of the jewel, and having ends adapted to be turned 25 in to engage the ends of the jewel, and a base member joining the side walls.

ALFRED F. REILLY.

CERTIFICATE OF CORRECTION.

Patent No. 2,044,510.

June 16, 1936.

ALFRED F. REILLY.

It is hereby certified that error appears in the printed specification of the above numbered patent requiring correction as follows: Page 1, second column, line 21, for the word "through" read throughout; and line 39, before "chain" insert a; and that the said Letters Patent should be read with these corrections therein that the same may conform to the record of the case in the Patent Office.

Signed and sealed this 11th day of August, A. D. 1936.

(Seal)

Henry Van Arsdale
Acting Commissioner of Patents.
